UNITED STATES PATENT OFFICE.

WILLIAM S. BRYANT, OF COHASSET, MASSACHUSETTS.

WAVE-MOTOR.

SPECIFICATION forming part of Letters Patent No. 693,369, dated February 18, 1902.

Application filed July 20, 1900. Serial No. 24,294. (No model.)

To all whom it may concern:

Be it known that I, WILLIAM S. BRYANT, of Cohasset, in the county of Norfolk and State of Massachusetts, have invented a new and useful Wave-Motor, of which the following is a specification.

My invention is a float connected with a platform by telescopic or like connections automatically actuating a pump to force water and air into a reservoir.

The drawing is a central vertical section of the best form of my new wave-motor.

In the drawing, A is the float, (shown as a buoy,) and B a tube depending from the buoy. The reservoir D and the cylinder C of the pump are mounted in the upper end of tube B, and the piston g of the pump is connected to platform H by means of the piston-rod g', spider h', and rods h. The platform H, rods h, spider h', and collar h² constitute a cage, which telescopes upon the tube B of the buoy, being guided thereon by two collars b², fixed to tube B, through which the rods h pass and by the upper one of which 25 the motion is limited. The substance of the matter is that platform H and buoy A must have relative motion and that the two parts of the pump, which must also have relative motion, must be connected one to the buoy 30 and the other to the platform, and suitable guides and stops are necessary as a practical matter to make the apparatus work properly and to enable it to stand the strains to which it is necessarily subjected, and all these 35 tails are of course capable of wide variation.

Cylinder C is provided with water-inlet valves g⁷ and also with air-inlet valves g³ and with an outlet-valve g⁸ at one side of piston g, but preferably with only water-inlet valve 40 g⁴ and water-outlet valves g⁵ at the other side of the piston.

The outlet-valve g⁸ is shown as opening directly into reservoir D, while the outlet-valves g⁵ are check-valves each in its pipe g⁶, which pipes open into reservoir D. The water-level rises in reservoir D until the air compressed in reservoir D above the water-level attains a pressure sufficient to force water mixed, of course, with some compressed 45 air through pipe f, and this outflow from pipe f is utilized in any desired manner, one example being that described in my Patent No. 666,259, dated January 22, 1901.

The operation is as follows: In the best 55 form of my apparatus the specific gravity of

platform H and the parts carried by it is greater than that of water, and consequently in still water platform H will be at its maximum distance from buoy A instead of its minimum distance, as shown in the drawing; 60 but this is not of very great importance, for if the specific gravity of the platform and its connections be less than that of water then the drawing correctly shows the relative position of the platform and buoy in still water; 65 but as the buoy is on the surface and the platform always well below the surface waves will move the buoy relatively to the platform, and that relative motion will actuate the pump, and water and air will be forced into 70 reservoir D, so that the water-level in reservoir D will rise rapidly, compressing air in reservoir D until the pressure is sufficient to force water mixed with compressed air through pipe f against the resistance caused 75 by the work which is done by this outflow through pipe f. The air which is absorbed and carried away by the water escaping from reservoir D is replaced by air from the pump, and thus the water in reservoir D is always 80 under air-pressure.

I use the terms "buoy" and "platform" simply because in the best form of my apparatus the motions of a buoy are opposed by a platform or drag; but of course I mean 85 to include all opposed bodies which are moved relatively by waves, provided their relative motion actuates a pump with an air-inlet as well as a water-inlet and that pump supplies a reservoir with both water and air. 90

What I claim as my invention is—

1. The wave-motor above described made up of a reservoir; a pump with both air and water inlets for forcing both water and air into that reservoir; and a buoy and platform 95 relatively movable by waves whose relative motion actuates the pump.

2. In combination, a buoy; a tube depending from that buoy; a platform; a cage extending from the platform and telescoping with the tube of the buoy; a pump whose cylinder and piston are moved relatively by the relative motion of the buoy and platform; and a reservoir into which the pump forces both water and air. 100
